UNITED STATES PATENT OFFICE

143,114

DESIGN FOR A MICROMETER CALIPER

Francis Cheyney Beekley, West Hartford, Conn.

Application May 24, 1945, Serial No. 119,699

Term of patent 14 years

(Cl. D52—1)

To all whom it may concern:

Be it known that I, Francis Cheyney Beekley, a citizen of the United States, residing at West Hartford, in the county of Hartford, State of Connecticut, have invented a new, original, and ornamental Design for a Micrometer Caliper, of which the following is a specification, reference being had to the accompanying drawing, forming a part thereof.

In the accompanying drawing:

Figure 1 is a front elevational view of a micrometer caliper showing my new design; and Fig. 2 is an edge view thereof.

I claim:

The ornamental design for a micrometer caliper, substantially as shown.

FRANCIS CHEYNEY BEEKLEY,
